UNITED STATES PATENT OFFICE.

CLARENCE WILLIAMS, OF WASHINGTON, DISTRICT OF COLUMBIA,
ASSIGNOR OF ONE-HALF TO JOHN GANEY, OF WASHINGTON,
DISTRICT OF COLUMBIA.

NON-REFILLABLE BOTTLE.

No. 834,544.

Specification of Letters Patent.

Patented Oct. 30, 1906.

Application filed August 7, 1905. Serial No. 273,028.

To all whom it may concern:

Be it known that I, CLARENCE WILLIAMS, a citizen of the United States, and a resident of the city of Washington, District of Columbia, have invented a new and useful Non-Refillable Bottle, of which the following is a specification.

The principal object of the invention is to provide a non-refillable attachment for bottles, jars, and the like which shall be simple in construction, inexpensive, and absolutely reliable.

Another object is to provide an attachment of the character mentioned which may be readily applied by hand and without the aid of special tools.

Other objects and advantages will be referred to hereinafter.

The nature, characteristic features, and scope of the invention will be more readily understood from the following description, taken in connection with the accompanying drawings, forming part hereof, and wherein—

Figure 1 is a view, principally in perspective, illustrating the application of a bottle-closure embodying features of my invention. Fig. 2 is a vertical sectional view thereof. Fig. 3 is a vertical sectional view of a modification in which a transverse strip or distance-piece is employed to hold the plug or valve away from the discharge-orifice. Fig. 4 is a top view of the neck of a bottle with the cap and stopper removed, showing the manner of applying the distance-piece. Fig. 5 is a sectional view of a modification of the cap, wherein tangs or spurs struck up from the cap act to space the valve. Fig. 6 is a sectional elevational view of a bottle-neck and cap, the neck having formed exteriorly thereof an upwardly-directed flange which surrounds the lower part of the cap. Fig. 7 illustrates a modified form of plug or cone valve. Fig. 8 is a view similar to Fig. 3 with the flange 18 added.

Referring to the drawings, 5 represents a member or part to be sealed or closed against refilling, which may be the neck of a bottle, jar, or the like. The part or neck 5 on its exterior is of varying diameter and is served with the shoulders 6 and 7. Interiorly the

neck is adapted for the reception of a valve, and by preference this consists of a cone or plug valve 8, whereof the seat is formed by the tapered wall 9.

10 represents a destructible stopper, which may embody a wafer of cork, paper, or any approved material. The stopper 10 covers the mouth of the bottle and is retained by a cap 11. The latter consists of a cone-shaped member having a discharge-orifice 12 in its top for outflow of the contents of the bottle and having at its base an inwardly and upwardly directed flange or gallery 13, which receives and retains a ring 14, bearing a plurality of tongues or spring-fingers 15, which when the cap is pressed down upon the neck spring inward and engage the shoulder 6.

Referring to Figs. 3 and 4, 16 represents a spacer or distance-piece which is interposed between the cap and the valve. The purpose of the part or member 16 is to prevent tampering with the valve and also to hold the valve away from the cap, and thus insure a free pouring of the contents.

Referring to Fig. 5, the same illustrates a varied form wherein the cap is formed or provided near its discharge-orifice with spurs or tangs 17, directed downwardly, so as to hold the valve away from said orifice.

Fig. 6 illustrates a varied form wherein the neck of the bottle is formed with an incircling flange 18, which surrounds the base of the cap when the latter is positioned and effectually precludes the introduction of an implement below the cap without breaking said flange.

Fig. 7 illustrates a varied form of the plug or cone valve wherein the top is ribbed or channeled, as at 19.

In practice, the bottle having been filled, the plug or valve is inserted, and the distance-piece or spacer, if desired, is applied as indicated in Figs. 3 and 4. The cap 11 is then shoved down onto the neck with the destructible stopper 10 in the end thereof. The cap 11 is now a permanent part of the bottle, and owing to the locking member 15 it is impossible to remove the same without breaking the bottle. The flange 18 (shown in Fig. 6) encircles the base of the cap, and

it is impossible to introduce a knife or other implement under the cap without breaking said flange. The stopper 10 being for temporary use only is made of paper, cork, or 5 any material that may be readily destroyed.

It will be obvious to those skilled in the art to which the invention appertains that modifications may be made in details without departing from the spirit and scope of 10 same. Hence I do not limit myself to the precise arrangement and construction of parts hereinabove described; but,

Having described the nature and objects 15 of the invention, what I claim as new and desire to secure by Letters Patent, is—

1. A device such as stated, comprising a neck exteriorly provided with shoulders and having a conical bore, which constitutes a valve-seat, a valve adapted to said seat, a 20 destructible stopper above the valve, a retaining-cap having a discharge-orifice and having upwardly-directed fingers which engage one shoulder, and bearing at its base against the other shoulder, and a distance-piece to hold the valve away from the cap, substantially as specified.

2. A device such as stated, comprising a neck exteriorly provided with a shoulder and with an upwardly-directed flange disposed 30 below the shoulder, and a cap having means to engage said shoulder and whereof the base enters between the flange and neck, substantially as specified.

3. A device such as stated, comprising a neck exteriorly provided with a shoulder and with an upwardly-directed flange disposed below the shoulder, a cap having means to engage said shoulder and whereof the base enters between the flange and neck, and a 40 stopper retained by the cap, substantially as specified.

4. A device such as stated, comprising a neck exteriorly provided with a shoulder and with an upwardly-directed flange disposed 45 below the shoulder, a cap having a central discharge-orifice and means to engage said shoulder and whereof the base enters be-

tween the flange and neck, and a stopper retained by the cap, substantially as specified.

5. A device such as stated, comprising a 50 neck provided exteriorly with an encircling upwardly-directed flange, a destructible stopper, a cap whereof the base enters between the flange and neck, and means to permanently retain the cap, substantially as 55 specified.

6. A device such as stated, comprising a neck exteriorly provided with a shoulder, a valve seated within the neck, a destructible stopper, a retaining-cap having a discharge- 60 orifice and means to engage said shoulder, and a spacer or distance-piece interposed between the valve and cap, substantially as specified.

7. A device such as stated, comprising a 65 neck exteriorly provided with a shoulder, a valve seated within the neck, a destructible stopper, a retaining-cap having a discharge-orifice in its top and terminating in a flange at its base, a ring seated in said flange, 70 and having a plurality of spring members to engage said shoulder, and means to hold the valve away from the discharge-orifice, substantially as specified.

8. A device such as stated, comprising a 75 neck exteriorly provided with a shoulder and with an upwardly-directed flange disposed below the shoulder, a cone-valve seated within the neck, a destructible stopper, a retaining-cap having a discharge-orifice and 80 terminating at its base in a bead or flange, which enters the flange of the neck, and a ring seated in the cap-flange and provided with a plurality of spring members adapted for engagement with said shoulder, substantially as 85 specified.

In testimony whereof, I have signed my name to this specification in the presence of two subscribing witnesses.

CLARENCE WILLIAMS.
